Primary Examiner — Paula Greene*(74) Attorney, Agent, or Firm* — TraskBritt(57) **CLAIM**

The ornamental design for a headphone, as shown and described.

DESCRIPTION

FIG. 1 is a front view of an embodiment of a headphone; FIG. 2 is a rear view of the headphone shown in FIG. 1; FIG. 3 is a left side view of the headphone shown in FIG. 1; FIG. 4 is a right side view of the headphone shown in FIG. 1; FIG. 5 is a top view of the headphone shown in FIG. 1; FIG. 6 is a bottom view of the headphone shown in FIG. 1; and, FIG. 7 is a perspective view of the headphone shown in FIG. 1, the opposite perspective view is a mirror image. The broken lines in FIGS. 1-7 are for environmental purposes only and do not form any part of the claimed design.

1 Claim, 6 Drawing Sheets(56)
